UNITED STATES PATENT OFFICE

104,026

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application December 10, 1936, Serial No. 66,419

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the design resides in the formation of the raised nubs simulating a wire mesh and forming a series of diamond shaped areas contiguously positioned and constituting a pattern of diamond shaped areas either singly or compositely.

I claim:

The ornamental design for a textile fabric or similar article of manufacture, substantially as shown and described.

JOHN F. GAUL, JR.
